CLAIM

The ornamental design of a control module, as shown and described.

DESCRIPTION

FIG. 1 is a perspective view of the control module;

FIG. 2 is a front view thereof;

FIG. 3 is a right side view thereof;

FIG. 4 is a left side view thereof;

FIG. 5 is a top end view thereof;

FIG. 6 is a bottom end view thereof; and,

FIG. 7 is a rear view thereof.

The stippled line sections of the control module is for purpose of illustrating portions thereof and form no part of the claimed design.
